CLUTCH MECHANISM FOR KNITTING MACHINES

Herbert E. Haehnel, Reading, Pa., assignor to Textile Machine Works, Wyomissing, Pa., a corporation of Pennsylvania

Filed July 2, 1959, Ser. No. 824,646

9 Claims. (Cl. 66—82)

The present invention relates to full-fashioned knitting machines and more particularly to an improved clutch mechanism adapted to disengage and engage the coulier mechanism from the main camshaft of such machines.

In flat full-fashioned hosiery machines of the general type referred to, the motions of the several cooperating instrumentalities for the performance of normal knitting and auxiliary loop transferring operations are derived from separate sets of cams on the main camshaft, a lengthwise shifting of the shaft through the medium of shifting cams being employed to bring one or the other of the sets of cams into operative position during continued operation of the machine. The shifting occurs during a predetermined angle of rotation of the camshaft which conventionally is 52°.

In order that the usual slur cams for operating the sinkers and yarn carrier operating means may be rendered idle during narrowing or other loop transferring operations, and may again be brought back into operation to be driven in synchronous relationship with the camshaft, it is the usual practice to drive the coulier cam, forming part of the coulier mechanism which is the motion transmitting means to these parts, from the main camshaft through a single tooth clutch.

The clutch includes a driven member held in fixed position axially of the machine but rotatable on the camshaft and a driving member rotatable and shiftable with the camshaft. The driving member is provided with a spring pressed driving pin or tooth adapted to enter an elongated recess in the driven member when the camshaft is shifted to the loop forming position and, upon contact with the forward wall of the recess, to rotate the driven member. It is essential that the tooth of the driving member penetrate the notch to a predetermined depth both to insure an efficient driving engagement and, also upon shifting of the camshaft to loop transferring position, to insure disengagement of the driving and driven members at a predetermined point in the rotation of the driven member to stop the coulier cam at a predetermined point. To this end in the conventional machine the parts are so proportioned that, as the camshaft is shifted longitudinally into loop forming position, the tooth reaches its predetermined depth of penetration as, or before, it contacts the forward wall of the recess. When attempts were made to speed up the machine requiring the driving of the camshaft at higher rotational speeds it was found that it was necessary to lengthen the camshaft shifting cams resulting in an increase in the angle of rotation of the camshaft during the shifting action to approximately 73° and a consequent lengthening of the spiral path traveled by the clutch tooth. Inasmuch as the timing of the shifting and clutch opening and closing operations are fixed by other factors and could not be changed the tooth did not penetrate the notch to the proper depth before it contacted the forward wall of the recess resulting in either failure of engagement of the clutch members or their inefficient engagement and consequent faulty operation of the machine.

The principal object of the invention is the provision in such a machine of an improved clutch which will insure proper engagement and disengagement of the clutch members irrespective of the speed of operation of the machine.

2

Another object of the invention is the provision of an improved clutch construction including means for advancing the spring pressed tooth of the driving member beyond its normal projection and a limiting member to adjust the projection of the tooth to a predetermined normal operating projection as the tooth enters into driving engagement with the driven member during shifting of the camshaft.

A still further object of the invention is the provision of a clutch mechanism as described above in which the spring pressed tooth is held locked in normal operating position when the clutch members are in driving engagement and during release of the clutching action, and in which the lock is thereafter released for the forward projection of the tooth in preparation for re-engagement of the clutch members.

The projection of the tooth of the driven member beyond its normal position when re-engagement of the clutch members is to occur enables the tooth member to enter the recess of the driven member at an early stage in the shifting of the camshaft thereby in effect shortening the spiral path it must travel to reach its proper depth of penetration of the recess, such proper depth being determined by the limiting member. The return of the tooth to its normal operating position by the limiting member and the locking of the tooth in such position during disengagement of the clutch members insures completion of disengagement and stopping of the couliering action at a predetermined and fixed point in the rotation of the camshaft.

With these objects in view, and others which will become apparent from the following detailed description of the illustrative embodiment of the invention shown in the accompanying drawings, my invention resides in the novel elements, features of construction and arrangements of parts in cooperative relationship as hereinafter more particularly pointed out in the claims.

In the drawings:

FIGURE 1 is a front elevational view of a portion of a full-fashioned knitting machine showing a clutch mechanism according to the invention for connecting in driving relation the camshaft and coulier mechanism of such machines;

FIG. 2 is an end elevational view of the mechanism as viewed from the right of FIG. 1, parts being shown in cross section;

FIG. 3 is an enlarged view of a portion of the mechanism of FIG. 1 showing the driving and driven portions of the clutch in disengaged position;

FIG. 4 is a cross-sectional view taken along the line 4—4 of FIG. 3;

FIG. 5 is a cross-sectional view taken along the line 5—5 of FIG. 3;

FIG. 6 is a cross-sectional view taken along the line 6—6 of FIG. 3;

FIG. 7 is a cross-sectional view taken substantially along the line 7—7 of FIG. 1; and

FIG. 8 is a cross-sectional view on an enlarged scale taken along the line 8—8 of FIG. 2.

Referring now to the drawings and more particularly to FIGS. 1 and 2 there is shown one of a series of transverse center frames 10, a front beam 11 and a back beam 12 forming part of the usual framework of a full-fashioned knitting machine. Supported by the framework

is a camshaft 15 which is arranged to be driven continuously in one direction during machine operation, and is further arranged to be shifted axially between knitting and narrowing positions. As shown in FIG. 1, the camshaft is in the position of normal knitting whereby a clutch mechanism 16 is employed to drive the coulier mechanism of the machine from the camshaft 15 through a pair of bevel gears 17 and 18 and a conventional coulier

cam (not shown). The shifting of the camshaft from left to right, as shown in FIG. 3, acts to bring into operative position the usual narrowing cams for the performance of the usual narrowing or similar loop transferring operations and to disconnect the clutch 16 to interrupt the operation of the couliering means. It will be understood that the shifting of the camshaft from knitting to narrowing position and back to knitting position again occurs, as is well known in the art, during a single revolution of the camshaft and is controlled in the usual manner through camshaft shifting cams and automatic mechanism actuated from the pattern chain (not shown) of the machine.

The bevel gear 17, acting as a driving gear for the coulier mechanism, is mounted for free rotation on the camshaft 15 and is maintained in meshing engagement with the gear 18 forming a part of the coulier drive by a collar 21 adjustably secured on a transverse carrying frame 22, which in turn is secured to the front and back beams 11 and 12, respectively. The collar 21 is arranged to ride in a groove 25 formed in the hub portions 26 of the driving gear 17.

The clutch mechanism 16 is of the single tooth type comprising cooperating male and female members 27 and 28, respectively. The female member 28 is formed as an integral part of the driving gear 17 and is provided with a recess 31 formed concentrically to the camshaft 15 and terminating in radially extending shoulders 32 and 33 (FIG. 4). The male member 27 is secured to the camshaft 15 to rotate therewith and is provided with a driving pin or tooth 36 and a locking pin 37 for the purpose of engaging the shoulders 32 and 33, respectively, of the recess 31 in the member 28 when the members 27 and 28 are in interlocked or driving relation. The pins 36 and 37 and their mountings are generally similar and like parts have been given the same reference characters. Thus each comprises a projecting tooth portion 40 and a shank portion 41 which is received in a circular recess 42 (FIG. 6) formed in the member 27. A compression spring 45 (FIGS. 7 and 8), confined within each recess 42 and seated between a plate 46 secured in the member 27 and a shoulder 47 formed by a recess 50 within the shank portion 41 of the pin, maintains the tooth portion 40 of the pin 36 or 37 in a projected position whereby a flat 51, formed on the tooth portion and lying in a plane radial to the camshaft 15, provides a surface contact when engaging its adjacent shoulder 32 or 33 of the recess 31 in the member 28.

To limit the extent of projection of the pins and also to prevent their rotation each of the pins has a shoulder 52 (FIG. 7) defined by the flat 51, engaging a plate 55 also secured to the member 27. Should for any reason the camshaft 15 be accidentally shifted back to normal position at the time when a narrowing or other loop transferring operation is desired, but more specifically at a point shortly after the drive pin 36 and shoulder 32 have been disengaged, the drive pin 36 would be depressed by, and ride on, the face 56 (FIGS. 3 and 4) of the member 28, but the locking pin 37 would then engage the shoulder. To prevent the pin 37 from driving the member 28 in such event it is provided with a beveled flat 57 (FIGS. 3 and 5) so as to ride off the shoulder 32 and be depressed by the face 56 of the member 28 until the drive pin 36 has again made proper contact with the shoulder 32. It will be understood from the above description that the pin 36 performs the driving function and pin 37 serves only as a stabilizer. Hence the clutch is referred to as a single tooth clutch.

The foregoing description is of the clutch construction conventionally employed in machines of the type referred to. In accordance with the instant invention means are provided to project the driving pin or tooth 36 beyond its normal position so that upon shifting of the camshaft from right to left as viewed in FIGS. 1 and 3 the tooth will enter the recess 31 at an earlier point than it would otherwise, to depress the pin to its normal projection, to

lock the tooth in its usual position until the camshaft is again shifted to the right, and to thereafter release the locking means to again project the tooth to its advanced position, all for the purposes previously pointed out.

5 Thus according to the present invention plate 55 is provided with a cutout 81 adapted to permit the projection of the driving pin 36 beyond its normal position at certain times under the pressure of compression spring 45. At other times it is maintained in its normal operating position as shown in FIG. 7 by one arm 60 (FIG. 6) of a lever 61 pivotally mounted on a shouldered stud 62 secured in the member 27. The arm 60 passes through a slot 65 formed in the member 27, and engages a shoulder 66 (FIG. 8) of a notch 67 formed in the shank portion 41 of the pin 36. The arm 60 is yieldably held in the notch 67 for engagement with the shoulder 66 by a flat spring 70, secured to the member 27 by a screw 71, the spring acting on a second arm 72 of the lever 61 to bias it in clockwise direction as viewed in FIG. 6. The extent of 10 engagement of arm 60 with the shoulder 66 is determined by a foot portion 75, formed at the extremity of arm 60, resting on the bottom surface 76 of the slot 65. Arm 60 and the inner end of pin 36 are provided with camming surfaces 63 and 64, respectively, to assist in resetting the lock as will be described. The lever 61 is arranged to be momentarily rotated on the stud 62 to release the arm 60 from engagement with the shoulder 66 by a roller 77 rotatably mounted on a bracket 80 (FIG. 2) secured to the back beam 12 in a position to lie in the 15 circular path of travel of arm 72 when the camshaft has been shifted to loop transferring position. On the other hand in the knitting position of the camshaft the position of the roller 77 in relation to the arm 72 is such that the arm will miss the roller as it rotates with the clutch member 27 and camshaft.

20 An adjustable set screw 82 is mounted within recess 31 adjacent shoulder 32, the head of the set screw serving as an abutment or limiting member to limit the penetration of the driving pin 36 into the recess as will hereinafter be described.

25 The operation of the clutch mechanism, as applied to a high speed machine in which the angle of rotation of the camshaft during shifting of the shaft between loop forming and loop transferring positions has been increased to approximately 73°, will now be described starting with the parts in the operating position shown in FIGS. 2 and 3. In such position the camshaft 15 has been shifted to the right or loop transferring position, the clutch members 27 and 28 disengaged, and the drive pin 36 is still locked in its normal operating position 30 by the arm 60 of the lever 61. Also in this position of the camshaft the arm 72 and the lever 61 has been moved into alignment with the roller 77 (see FIG. 3). Thereupon as the camshaft continues to rotate during its single 35 turn in the narrowing cycle, arm 72 will be brought into contact with roller 77 and momentarily rotated counterclockwise, as viewed in FIG. 6, by the roller to disengage arm 60 from the shoulder 66 and release pin 36 to be projected beyond its normal operating position by the spring 45, namely until the shoulder 52 engages the plate 55 at the cutout portion 81. As the arm 72 passes roller 77 the spring 70 again biases the lever 61 clockwise, as viewed in FIG. 6, to re-engage the foot portion 75 with the surface 76 with the arm 60 lying to the rear of the projected pin 36.

40 During the shifting of the camshaft to its loop forming position, to the left in FIG. 3, the pin 36, traveling in a spiral path set up by the combined rotative and axial movements of the shaft, enters recess 31 and as it continues in such path contacts the head of stud 82 shortly 45 before it reaches shoulder 32. This is brought about by the extra extension of the pin 36. However inasmuch as the camshaft, due to its shifting requiring an increased angle of rotation, has not been completely shifted by this time, as it completes its movement to the left pin 36 is 50 depressed within its recess 42 against the action of spring 75

45, and the interaction of cam faces 63 and 64 pushes the arm 60 outwardly where it is held until the pin is depressed sufficiently to permit arm 60 to swing inwardly behind shoulder 66 under the load of spring 70. At this time the pin is again in its normal operating position.

When the camshaft is shifted to the right into loop transferring position the pin 36 is retained in normal operating position by the latch structure, comprising the arm 60 and shoulder 66, until the clutch has been disengaged and arm 72 again brought into contact with roller 77.

It will be understood that the improvement specifically shown and described by which the above described results may be obtained, can be changed and modified in various ways without departing from the scope of the invention disclosed and hereinafter claimed.

I claim:

1. In a knitting machine including a clutch comprising driving and driven members relatively shiftable between engaged and disengaged positions during rotational movement of one of said members, a tooth having a normal operating position carried by one of said members and a recess in the other of said members defining an abutment for interengagement with said tooth when said tooth is within said recess, the improvement comprising means to project said tooth to an advanced position beyond said operating position, a limiting member in the path of movement of said tooth during relative shifting of said members in a clutch engaging direction to depress said tooth to its normal operating position, and means to lock said tooth in its normal operating position when depressed by said limiting member.

2. In a knitting machine as claimed in claim 1 means to release said locking means when said clutch members are disengaged.

3. In a knitting machine as defined in claim 1 wherein said tooth comprises a pin having a shoulder thereon and there is a spring biasing said pin to said advanced position and there is a stop for contact with said shoulder to define said advanced position.

4. In a knitting machine as defined in claim 1 wherein said tooth is carried by said driving member and said locking means comprises cooperating means on said driving member and said tooth.

5. In a knitting machine as defined in claim 1 wherein said tooth comprises a pin carried by said driving member, and said locking means comprises a lever having an arm swingable into and out of locking engagement with said pin, and a second arm, and there is means on said machine in the path of movement of said second arm when said clutch is disengaged to depress said second arm and disengage said first arm from said pin.

6. In a knitting machine as defined in claim 1 wherein said limiting member comprises an adjustable abutment member in said recess.

7. In a knitting machine as defined in claim 1 wherein said limiting member comprises an adjustable abutment member in said recess, said tooth is carried by said driving member and comprises a spring pressed pin having a forward end for contact with said abutment member and a notch adjacent the rear end thereof, and said locking means comprises a lever having an arm for holding engagement in said notch and spring means to bias said arm toward said notch.

8. In a full-fashioned knitting machine including a camshaft, means for shifting said shaft between loop forming and loop transferring positions, a coulier mechanism, means to drive said coulier mechanism from said camshaft when said camshaft is in loop forming position, said last named means comprising a clutch including a driven member in fixed position on said machine and a driving member carried by said camshaft for shifting movement therewith, said driven and driving members including a shoulder and a spring pressed tooth respectively for interengagement when said shaft is shifted to loop forming position, said tooth having a normal operating position, the improvement comprising means for projecting said tooth beyond said normal operating position when said driving and driven members are disengaged, means in the path of movement of said tooth during engagement of said driving and driven members for depressing said tooth to its normal operating position, means to lock said tooth in its normal operating position and means to release said locking means when said driving and driven members are disengaged.

9. In a knitting machine as defined in claim 8 wherein said tooth comprises a pin spring biased toward said driven member and said locking means comprises a notch in said pin and a lever carried by said driving member having an arm received within said notch, a second arm, and means biasing said first arm toward said notch, and said releasing means includes means in the path of movement of said second arm for momentarily depressing said second arm.
